UNITED STATES PATENT OFFICE

129,654

DESIGN FOR A LAPEL CLIP OR SIMILAR ARTICLE

Christian Arpad Jakobb, Bayside,
Long Island, N. Y.

Application August 19, 1941, Serial No. 102,939

Term of patent 3½ years

To all whom it may concern:

Be it known that I, Christian Arpad Jakobb, a citizen of the United States of America, residing in Bayside, Long Island, county of Queens, and State of New York, have invented a new, original, and ornamental Design for a Lapel Clip or Similar Article, of which the following is a specification, reference being had to the accompanying drawing, forming part thereof, wherein,

I claim:

The ornamental design for a lapel clip or similar article, substantially as shown.

CHRISTIAN ARPAD JAKOBB.
